UNITED STATES PATENT OFFICE.

JOHN O. MCKEAN, OF WESTFIELD, MASSACHUSETTS, ASSIGNEE TO FOSTER MACHINE COMPANY, OF WESTFIELD, MASSACHUSETTS, A CORPORATION OF MASSACHUSETTS.

POWER-DRIVEN DEVICE FOR AUTOMATICALLY UNTWISTING YARN TO REMOVE THE KINKS THEREFROM.

Application filed November 11, 1925. Serial No. 63,366.

It has been practically impossible to keep yarn from kinking as it passes from the yarn supply to the warping machine. This is especially true when the warping machine 5 stops and the yarn is at rest.

The object of my invention is to provide a power driven device arranged to exert an untwisting rolling action on the yarn as it passes therethrough, to automatically untwist and remove the kinks, said device in 10 the present instance comprising a power driven vertical support and a pair of coaxial plates of considerable diameters carried thereby, the lower plate being fixed to said support and the upper plate being gravity operated and rotatable upon the lower plate at a higher angular speed by the yarn in 15 its passage between the plates for exerting the untwisting rolling action on the yarn. 20 The above untwisting device is preferably used in connection with a compensating device which operates to keep the yarn comparatively taut whether the yarn is running or at rest, thereby tending to keep the kinks 25 from forming in the yarn especially when the yarn is at rest.

A practical embodiment of my invention is represented in the accompanying drawings, in which—

30 Fig. 1 represents a detail side view of a creel with my power driven devices for automatically untwisting the yarn included therein.

Fig. 2 represents a section taken in the 35 plane of the line II—II of Fig. 1, looking in the direction of the arrows.

Fig. 3 represents a detail section on an enlarged scale, showing a cop, the compensating device and the untwisting device.

40 Fig. 4 represents a detail horizontal section taken in the plane of the line IV—IV of Fig. 3, looking in the direction of the arrows.

The creel frame is denoted by 1, the cops 45 2 are arranged in a plurality of vertical rows, the holders 3 for the cops of each vertical row being carried by a vertically disposed supporting bar 4 pivoted in the creel frame 1 to rock on a vertical axis, to swing 50 the cops to and from their doffing position.

In proximity to each vertical supporting bar 4, I mount a vertically disposed rod 5 around which rod the yarns are wound as they pass from their cops to the warping

machine (not shown herein). I have found 55 that by winding the yarn around the bar 5 as it leaves the cop, the bar operates to keep the yarn comparatively taut whether the yarn is or is not running, thereby tending to take the kinks out of the yarn when the 60 yarn is running and also to keep the kinks from forming when the yarn is at rest.

The power driven device for automatically untwisting the kinks from the yarn by a 65 rolling action thereon as it passes through the device comprises a vertically disposed bar 6 rotatably mounted in the creel frame 1 adjacent to the vertically disposed yarn compensating rod 5, and a pair of upper and lower coaxial plates 7 and 8 of considerable 70 diameters. The lower plate 8 is secured in its proper position on the bar 6 by the set screw 9 and the upper plate 7 rests by gravity on the lower plate 8 and is freely rotatable thereon, which upper plate may be provided with one or more weights 10, if so desired.

The vertically disposed bar 6 and the lower 80 plates 8 fixed thereto are slowly rotated at a predetermined speed by providing the bar 6 with a worm gear connection 11, 12 with a shaft 13 driven from the warping machine (not shown herein).

In operation.—When the yarn is running it will rotate the upper plate at a higher angular speed than the lower plate is being rotated, thus causing the plates to exert an untwisting rolling action on the yarn which automatically untwists the kinks therefrom. The positive rotation of the lower plate ensures the wiping clean of the coaxial surfaces of the two plates of the unkinking device by the yarn as it passes therethrough.

By making the plates 7 and 8 of considerable diameters I am enabled to obtain a 95 very high surface speed at the periphery of the upper plate, the lower plate being positively rotated at a lower speed, thus exerting an extended untwisting rolling action on the yarn and also tending to throw 100 foreign matter outwardly, away from between the plates, it being understood that the yarn in passing through the plates acts to wipe their coaxial surfaces clean and keep them polished.

I am aware of the tension devices of the art of somewhat similar construction to the herein-described kink removing device, but

the washers of these tension devices of the art are universally very much smaller than the kink removing plates of the present invention. These tension devices of the art 5 are incapable of acting to untwist the kinks from the yarn and are not intended to act for this purpose. In fact these tension devices tend to bit the yarn and to run the twist back and form kinks therein. In 10 practice I have found that by making the plates of my kink removing device about four inches in diameter as compared to the one and one-half inch diameter of the washers of the tension devices of the art, I am 15 enabled to obtain extended contact with the yarn and an untwisting rolling action thereon sufficient to remove the kinks therefrom.

What I claim is:—

1. A yarn supply cop and a device comprising a pair of coacting rotatable plates having an extended contact with the yarn and operable to remove the kinks therefrom by an extended untwisting rolling action thereon as it passes therethrough, said plates 20 having diameters greater than one-half the length of the cop from which the yarn is being drawn, and means for rotating one of said plates.
2. A yarn supply cop and a device comprising a pair of coacting rotatable plates having an extended contact with the yarn and operable to remove the kinks therefrom by an extended untwisting rolling action thereon as it passes therethrough, said plates 25 having diameters greater than one-half the length of the cop from which the yarn is being drawn, means for rotating one of said plates, and a yarn compensating device engaging the yarn as it passes from the yarn 30 supply to the kink removing device, operating to keep the yarn comparatively taut when the yarn is running and at rest.
3. A yarn supply cop and a device comprising a rotatably mounted vertical support and a pair of coacting plates carried thereby having an extended contact with the yarn and operable to remove the kinks therefrom by an extended untwisting rolling action thereon as it passes therethrough, 35 said plates having diameters greater than one-half the length of the cop from which the yarn is being drawn, the lower plate being fixed to said support and the upper plate being gravity operated, and means for 40 rotating said vertical support.
4. A yarn supply cop and a device com-

prising a rotatably mounted vertical support and a pair of coacting plates carried thereby having an extended contact with the yarn and operable to remove the kinks 60 therefrom by an extended untwisting rolling action thereon as it passes therethrough, said plates having diameters greater than one-half the length of the cop from which the yarn is being drawn, the lower plate 65 being fixed to said support and the upper plate being gravity operated, means for rotating said vertical support, and a yarn compensating device engaging the yarn as it passes from the yarn supply to the kink 70 removing device, operating to keep the yarn comparatively taut when the yarn is running and at rest.

5. A plurality of yarn supply cops and a plurality of devices comprising a common rotatably mounted vertical support and a plurality of pairs of coacting plates carried thereby having an extended contact with the yarn and operable to remove the kinks therefrom by an extended untwisting rolling 75 action thereon as they pass therethrough, said plates having diameters greater than one-half the length of the cops from which the yarn is being drawn, the lower plate of each pair being fixed to said support and the upper plate of each pair being gravity operated, and means for rotating said vertical support.

6. A plurality of yarn supply cops and a plurality of devices comprising a common rotatably mounted vertical support and a plurality of pairs of coacting plates carried thereby having an extended contact with the yarn and operable to remove the kinks therefrom by an extended untwisting rolling 80 action thereon as they pass therethrough, said plates having diameters greater than one-half the length of the cops from which the yarn is being drawn, the lower plate of each pair being fixed to said support and the upper plate of each pair being gravity operated, and means for rotating said vertical support.

7. A plurality of yarn supply cops and a plurality of devices comprising a common rotatably mounted vertical support and a plurality of pairs of coacting plates carried thereby having an extended contact with the yarn and operable to remove the kinks therefrom by an extended untwisting rolling 85 action thereon as they pass therethrough, said plates having diameters greater than one-half the length of the cops from which the yarn is being drawn, the lower plate of each pair being fixed to said support and the upper plate of each pair being gravity operated, and means for rotating said vertical support.

In testimony, that I claim the foregoing as my invention, I have signed my name 90 this 9th day of Nov., 1925.

JOHN O. McKEAN.
